H. F. WHEELER, OF BOSTON, MASSACHUSETTS.

Letters Patent No. 72,485, dated December 17, 1867.

IMPROVEMENT IN PEN-HOLDERS.

The Schedule referred to in these Letters Patent and making part of the same.

TO ALL WHOM IT MAY CONCERN:

Be it known that I, H. F. WHEELER, of Boston, in the county of Suffolk, and State of Massachusetts, have invented an Improvement in Pen-Holders; and I do hereby declare that the following, taken in connection with the drawings which accompany and form part of this specification, is a description of my invention, sufficient to enable those skilled in the art to practise it.

In using writing-pens, it is often convenient and sometimes necessary to use two pens, containing two kinds of ink, as a red ink and a black ink, or two kinds of pens, as a coarse one and a fine one, and my invention has for its object such a construction as shall enable two pens to be used without change of stock or handle, the invention consisting in combining, with a single pen-stock or handle, holders or sockets for two pens, which holders or sockets fork out from one end of the handle (when the instrument is ready for use) in such manner that either may be dipped into an ink-bottle without disturbing the other, and may be freely held and guided in writing, the same as if the pen were in a common handle.

It is this construction that constitutes my invention, and an instrument embodying the improvement is shown in the drawings.

a denotes the handle, *b b* the pen-sockets, and *c c* the two pens. Each pen-socket, *b*, is formed on the end of a thin metal spring, *d*, and the two springs uniting are inserted fast into the end of the stock or handle *a*. A tube, *f*, slides upon the handle, and by forcing it outwardly, as seen at *C*, the pens are brought together in convenient position for the instrument to lie upon a desk or table, or on a pen-rack, while, by sliding the tube back upon the handle, as seen at *A* and *B*, the pen-sockets spring apart, bringing each pen into position for use, as will readily be seen.

Either pen may be used with one kind of ink when the two are brought together, and in this case the two may be used as a fountain-pen, not only holding in each the amount of ink commonly held in an ordinary pen, but also holding a considerable supply of ink between the sockets, which ink flows freely down into the pens as the ink flows therefrom in writing.

The construction and arrangement of the pen-sockets may be modified from that shown, it being understood that I do not limit my invention to the means of applying the sockets, but design to cover broadly combining two pen-sockets with a handle in such manner that a pen in either socket may be used independently of the other, as may be desired.

I claim a pen-holder, having sockets for two pens, substantially as described.

H. F. WHEELER.
